UNITED STATES PATENT OFFICE.

JOHN PALMER, OF FORT SCOTT, KANSAS, ASSIGNOR TO HIMSELF, AND JAMES F. DRAPER, OF CHICAGO, ILLINOIS.

MANUFACTURE OF VINEGAR.

Specification of Letters Patent No. 29,550, dated August 7, 1860.

To all whom it may concern:

Be it known that I, JOHN PALMER, of Fort Scott, in the county of Bourbon, Kansas, have invented a new and improved method 5 of rapidly manufacturing vinegar, a new material for filling vinegar apparatus, and an improvement in mode of constructing apparatus; and I do hereby declare that the following is a full and exact description of 10 the same, reference being had to the annexed drawings, making a part of this specification.

The nature of my invention consists in the preparing an apparatus and filling that 15 will expose the greatest amount of the liquid used for the production of vinegar, to the action of the greatest quantity of atmospheric air at all periods of time during acetification. Also to increase and perpetuate 20 the acetous fermentation for any required time without deterioration in quality or being of necessity renewed, and without the use of extraneous heat, the filling when saturated with the proper proportions of 25 alcohol and saccharine matter, generating its own heat, and perpetuating it in winter as well as in summer, the constituents for manufacture being used without reference to temperature, while by the ordinary slow 30 German process the fluid used must be heated to from 70° to 83° Fahrenheit.

My apparatus requires the fluid to be passed through it but once to accomplish the most perfect acetification, thus allowing 35 the manufacturer to be sure of realizing a certain number of barrels each day, the pure vinegar running off at the base of the pile as fast as the stock is fed on at the top for any number of months (my exper- 40 ence extends through two years), the ordinary process requiring the fluid to be passed through the series of apparatus time and again. By my process the vinegar may be made by a single running of a desired 45 strength at the option of the maker, and at his most perfect control.

To enable others skilled in the art to construct and use my apparatus and invention I will proceed to describe its construction 50 and operation.

Instead of single tubs ten to twenty feet in height, my apparatus consists of a series of tubs one upon another raised to the height at least of thirty feet and higher, as 55 I wish to make my vinegar of greater proof.

I use tubs of the length and shape of hogsheads to secure the required strength from hoops for the altitude. In the lower or ground tub of my series I allow the bottom head to remain, removing the upper head. 60 In the center of the lower head bore a four inch hole and insert a tube closed at the top fitting the hole water tight. Tube marked A in the drawings accompanying. This tube I pierce with four holes, one inch 65 in size equidistant near upper end as seen at B, C, in drawing, inclining from below up to prevent the vinegar from wasting through them. Tube sixteen inches in length. On bottom of tub at points equi- 70 distant from tube as seen in drawing D, E, F, G, I set four pieces of pine six by six, sixteen inches long, upon which and tube rest a perforated shelf, colander, or false bottom pierced with numerous holes, com- 75 municating with each other by a groove to allow the vinegar in its descent to pass readily. False bottom shown in drawing marked H, I. Between the two bottoms in the staves of the cask nearest the upper or 80 false bottom I bore one hole two inches in size in each stave as seen in drawing marked 1, 2, 3, &c. These holes and the tube with perforations are to freely admit air to the base of apparatus, one of the principal 85 points gained by this apparatus being the most perfect admission of air to all portions of the filling, thus keeping up the requisite supply of oxygen to promote and perfect acetous fermentation. Upon this false bot- 90 tom I commence to place my filling (this filling is what I most particularly claim as my invention).

My filling consists of round corn cobs placed in regular layers alternately, none 95 to stand perpendicularly in the tub since they would rapidly conduct the fluid along their length, but all to lie horizontally for the purpose of allowing the food to pass over their whole surface slowly, the inter- 100 stices and cells in the cob permitting free circulation of air through the whole mass, the peculiar conformation of the filling, "the corn cob," offering the greatest amount of fluid used for manufacture in the thinnest 105 sheets to the greatest amount of atmospheric air, and from the construction of my apparatus (height being referred to) for the longest continuous time, thus securing oxidation thoroughly and completely as before 110

described in the shortest possible time, none of which results can be perfectly attained by any other method, every other variety of filling requiring to be frequently replenished 5 or renewed, the fluid too requiring to be raised by heat to 80° Fahrenheit or thereabout to procure acetification, and also absolutely impossible with it to produce the required result (acetification) without passing 10 the fluid through many times, thus enhancing the labor and delaying the time, while my filling, becoming very shortly inverted and filled with acetic acid, is preserved and actually grows better and more valuable by 15 increasing age. Cask number two in the series, as seen in the drawing 2, I chamfer at lower end on outside to fit inside of cask 1, at top. Having placed this to fit accurately I continue to lay up my filling as in 20 first cask and thus with each cask continuously until I have attained the desired altitude. I then invert a tub, leaving in an upper head, this to be pierced with five holes equidistant from center, as seen in the draw- 25 ing J, K, L, O. S, a groove running from one to the other to permit the fluid to flow readily into the pile. In this upper head

bore two inch hole, as seen in diagram marked Y, for the escape of air coming from lower part of apparatus, thus keeping up 30 the circulation through the pile. I have thus secured a closed tube, save at the bottom, my center air tube and air holes in staves, and at top my feeding holes, and hole for escape of air. Above this pile, as seen 35 in diagram, a feeding tub is placed—capacity varied according to size of pile or number of series. The fluid for making vinegar by this process is same as for the old German method fed onto the upper head of pile 40 through cock X, as seen in diagram. With my apparatus the fluid requires but one passing through for the most perfect acetification, requiring about twelve hours to be fully complete when passed through an ap- 45 paratus from thirty to fifty feet in height.

What I claim as my invention and desire to secure by Letters Patent is—

The discovery of a material for filling vinegar apparatus "the corn cob."

JOHN PALMER.
